MESSAGE PAD HOLDER

William E. Regan, Hillsborough, Calif., assignor to Regan Industries, Inc., San Bruno, Calif., a corporation of California

Filed Aug. 26, 1963, Ser. No. 76,357

Term of patent 7 years

(Cl. D74—1)

I claim:

The ornamental design for a message pad holder, substantially as shown.
